US00D878417S

(12) **United States Design Patent** (10) **Patent No.:** **US D878,417 S**
(45) **Date of Patent:** **** Mar. 17, 2020**

(54) **DISPLAY SCREEN WITH ICON**

(71) Applicant: **Google LLC**, Mountain View, CA (US)

(72) Inventor: **Sehee Lee**, Brooklyn, NY (US)

(73) Assignee: **Google LLC**, Mountain View, CA (US)

(**) Term: **15 Years**

(21) Appl. No.: **29/695,508**

(22) Filed: **Jun. 19, 2019**

Related U.S. Application Data

(63) Continuation of application No. 29/643,547, filed on Apr. 10, 2018, now abandoned.

(51) **LOC (12) Cl.** **14-04**

(52) **U.S. Cl.**

(57)

CLAIM

The ornamental design for a display screen with icon, as shown and described.

DESCRIPTION

The sole FIGURE is a front view of a display screen with icon showing the new design.

The broken lines of uneven length show the display screen and form no part of the claimed design.

1 Claim, 1 Drawing Sheet
